UNITED STATES PATENT OFFICE.

GUSTAVE J. JACCARD, OF NEW YORK, N. Y.

ALARM-CLOCK.

1,074,436.

Specification of Letters Patent. Patented Sept. 30, 1913.

Application filed April 10, 1912. Serial No. 689,889.

To all whom it may concern:

Be it known that I, GUSTAVE J. JACCARD, a citizen of the United States, and a resident of the city of New York, borough of Manhattan, in the county and State of New York, have invented a new and Improved Alarm-Clock, of which the following is a full, clear, and exact description.

My invention relates to an improvement 10 in alarm clocks designed especially for the benefit of deaf people; and the object thereof is to produce an alarm clock provided with the usual bell that rings at the appointed moment; and likewise with a lamp 15 which can be caused to light up at the same time, throwing upon the face of a person who has lost his sense of hearing a light intense enough to wake him.

My invention is further provided with appropriate controlling mechanism to enable 20 the clock to be set so that either the bell or the lamp will be actuated, or both actuated together, according to the manner in which the parts are set.

Reference is to be had to the accompanying drawings forming a part of this specification, in which the same characters of reference indicate the same parts in all the views.

Figure 1 is a front view of my improved alarm clock, showing part of the interior mechanism; Fig. 2 is a front elevation of the controlling devices; Fig. 3 is a side elevation of the parts shown in Fig. 2; Fig. 35 4 is a detail view, showing the electric circuit for the lamp and the manner in which the same is closed; and Fig. 5 is a sectional view showing the mechanism for releasing the alarm actuating parts when the appointed time arrives, the view being taken 40 along the line 5—5 of Fig. 2, looking upward.

On the drawings, the numeral 1 represents my improved alarm clock as a whole, 45 and 2 the face of the same.

3 and 4 are the minute hand and the hour hand, respectively, and 5 is a dial having a pointer 6 mounted upon a spindle 7, this dial having numbers from one to twelve marked 50 thereon, and the pointer 6 being set opposite

these numbers, according to the hour at which the sleeper wishes to awake. This spindle 7 is mounted in the framework of the body of the clock and can be manipulated by a knob at the rear of the clock in 55 the ordinary and usual way. Behind the face of the clock and inside of the same it is provided with a disk 8 rigidly mounted upon the spindle 7, as shown in Fig. 2, and the disk 8 has a notch 9 in its rear face, 60 which, when the hour arrives, receives a pin 10 carried by a gear wheel 11. This gear wheel is loosely mounted upon the spindle 7 so that it can be rotated thereon and slide along the same as well, and it is engaged to 65 be actuated by a pinion 12 on the spindle of the hour hand 13. The width of the face of this pinion 12 is sufficient to preserve the meshing engagement between the gears 11 and 12 when the spindle 11 slides to a cer- 70 tain extent along the spindle 7.

14 is a spring member riveted at its upper end to a framework 15, which supports the motor mechanism inside of the clock, and this spring member passes behind the gear wheel 11, having an aperture which loosely receives the spindle 7; and beyond this gear wheel 11 this spring member 14 has a projection 16 for a purpose which will appear later. The projection 16 marks the extremity of 80 the spring member 14, and connected to this extremity is a piece of insulating fiber 17, supporting at its lower end a contact 18, to which is secured a conductor 19. 20 is a similar strip of insulating fiber secured to 85 the framework 15, and carrying in its outer end a contact 21, connected to a conductor 22. These two conductors are in circuit with a source of electricity shown in Fig. 4, and a lamp 23 of the ordinary incandescent 90 type; and this lamp is partly inclosed by a reflector hood 24.

25 is a locking lever which engages the projection 17 and holds the contacts 18 and 21 apart. It is pivoted at 27 on a plate 26 95 secured to the frame 15, and its lower end is out-turned as shown at 28. This out-turned end 28 passes through a hole in the end of an arm 29 mounted rigidly upon a spindle 31 supported by the plate 26, and 100

having secured thereon an operating arm 30 carrying at its outer end a pin or stud 32.

As stated above, the arms 29 and 30 are fixed on the spindle 31, which is rotatable in the plate 26, and on the inner end of this spindle is mounted an arm 33, having its end bent rearward, as shown in Fig. 3. This arm passes beneath the clapper arm 34 of an alarm bell 35, this clapper arm being secured to a spindle 36 rotatably carried by the framework 15, and having an operating arm 37 projecting therefrom. This operating arm is actuated by means of a toothed wheel, which is rotated by a spring motor, as is usual in alarm clocks of this type. The numeral 38 represents another arm projecting from the spindle 36; and 39 represents a projection extending rearward from the spring member 14 into engagement with the arm 38. When the locking lever 25 engages the projection 16 on the spring member 14, it forces this lever rearwardly, and the projection 39 moves into the path of the arm 38 and prevents the clapper from ringing the bell, which will be readily understood.

40 is a curved slot in the front of the body of the clock below the face of the same, and into this curved slot projects the pin 32.

41 is a mark adjacent the lower edge of the slot to indicate the position of the pin when the lamp is to be lighted, without releasing the audible alarm device including the bell 35.

35 The manner of operation of my alarm device will now be described.

Suppose one wishes to cause the alarm to be actuated at a given hour: He turns the spindle 7 to bring the index pointer 6 to the corresponding number on the dial 5. This turns the disk 8 and causes the notch therein to be set a certain angular distance from the pin 10 on the gear 11. The gear 11 is rotated by the pinion 12, and when the appointed hour arrives, the pin 10 will be carried into position to register with the notch 9; and when this happens the resiliency of the spring 14 will cause the lower end thereof carrying the projection 16 on

50 the contact 18, to move outward; that is, toward the observer, referring to the position of the parts in Fig. 2. This movement of the spring member 14 will cause the gear 11 to slide along the spindle without getting disengaged from the pinion 12, and force the pin 10 into the notch 9 of the disk 8. In order to permit this movement of the spring member 14, the arm 30 must be moved to the left to throw the locking lever 25 away from the projection 16. If the lever 25 is moved to the position shown in Fig. 2, that is, so as to bring the pin 32 opposite the mark 41 in the middle of the slot 40, the upper end of the arm 25 will

65 be moved away from the contact 16, but

the arm 33 will not be moved far enough to release the clapper arm 35. Consequently, when the spring member 14 moves forward, as described, the projection 39 will move away from the arm 38, releasing this arm, 70 but the bell will be prevented from ringing by the arm 33. Hence, the movement of the spring member 14 can only result in allowing the contacts 18 and 21 to come together, closing the circuit and illuminating the lamp 23. This throws a strong light on the sleeper's face and wakes him. This mode of using my invention is intended especially for the benefit of deaf people who, having lost the sense of hearing, could not be awakened by means of the sound of the bell 35. For persons having normal hearing the bell 35 can of course be used. This is accomplished by pushing the pin 32 over to the extreme left end of the slot 40. 85 By this movement the arm 33 is moved out of obstructing position with respect to the clapper 34; but until the hour of waking arrives the projection 39 carried by the spring member 14 engages the arm 38 and holds the clapper 35 against movement. As soon as the pin 10 and notch 11 come into engagement, the spring member 14 moves forward as before, carrying the projection 39 out of obstructed position, releasing the clapper 34 and at the same time closing the electric circuit. The lamp now lights up and the bell 35 rings at the same time, and the sleeper not only wakes, but finds that the light has been made for him.

From the above description it will be seen that my invention is a decided improvement upon the ordinary form of alarm clock which has no electric connection to illuminate the room when the hour of rising approaches. The lamp 23 can be an ordinary incandescent lamp and connected to the conductors of an ordinary supply circuit, these conductors leading to the switch formed by the contacts 18 and 19. Either the lamp can be caused to light itself alone at a given hour, or the lamp and the alarm can be set to be actuated together; and in the latter case, after the alarm has rung itself out, the lamp 23 will continue burning as long as may be desired.

The pin 32 must, of course, be moved away from the right-hand end of the slot 40 in order to put the alarm clock in a position to operate at all at the time set; otherwise the locking lever 25 will hold the spring member 14 against movement, regardless of the relative position of the recess or notch 9 and pin 10. When the pin 32 is moved as far as the mark 41, the lamp will light up at the required moment, and when it is moved over to the other end of the slot both the lamp and the bell will be actuated together when the controlling parts come into operative position.

I wish to have it understood that the above description is illustrative only, disclosing but one embodiment of my invention, and that I do not care to be limited to the details thereof, except in so far as is expressly indicated in the accompanying claims.

Having thus described my invention, I claim as new and desire to secure by Letters Patent:

1. In a device of the kind described, the combination of locking means, an alarm bell, a clapper therefor, an illuminating device, means for controlling said illuminating device, and means for actuating the locking means to release the controlling means without releasing the clapper for the said bell.

2. In a device of the kind described, the combination of an illuminating device, means for controlling the actuation thereof, an audible alarm device, means for preventing the operation thereof carried by the controlling means, means for preventing the actuation of the controlling means and the audible alarm device, said means being movable to release the controlling means and the audible alarm device, and means for operating the said controlling means, whereby when the same is operated the audible alarm device and the illuminating device will be operated simultaneously.

3. In a device of the kind described, the combination of a pair of contacts, means for connecting an illuminating device to the same, means for movably mounting one of said contacts, means for controlling the movement of said last-named means to permit said contacts to be brought together, a locking lever for holding the movable contact away from the other contact, manual means for controlling the locking lever to move the same to release position, a bell having a clapper, said manual means having a projection to engage the clapper to prevent the same from ringing the bell, and a projection carried by the means carrying the movable contact for preventing the operation of the clapper, whereby when the manual means is moved to intermediate position it releases the contacts to enable them to be brought together without releasing the clapper, and when moved to extreme position it releases the clapper also.

4. In a device of the kind described, the combination of a pair of contacts, means for connecting an illuminating device to the same, means for movably mounting one of said contacts, means for controlling the movement of said last-named means to permit said contacts to be brought together, locking means for holding the movable contact away from the other contact, a bell having a clapper, said locking means having a projection to engage the clapper and prevent the same from ringing the bell, and a

projection carried by the means carrying the movable contact for preventing the operation of the clapper, whereby when the locking means is moved into an intermediate position it releases the contacts to enable them to be brought together without releasing the clapper, and when moved to extreme position to enable the clapper to be operated also.

5. A signal, including a movable element, a second signal, means for controlling the second signal, and a locking device for engagement with both the said element and the controlling means, said locking device being movable out of engagement with the controlling means without being moved out of engagement with the said element, or movable out of engagement with the actuating means also.

6. In a device of the kind described, the combination of a signal, including a movable element, a second signal, means for controlling the second signal, a locking device to engage the said element and the controlling means, and means for causing the controlling means and the said element to tend to become active at a given instant, said locking means being movable out of engagement with the controlling means only or out of engagement with both the controlling means and the said element together, whereby when the aforesaid instant arrives the second signal alone or the second signal and the first signal together will be energized according to the position of the locking means.

7. In a device of the kind described, the combination of a signal, including a movable element, a second signal, means for controlling said second signal, said controlling means having a projection for engaging the said element and preventing movement thereof, and a locking device engaging the controlling means and the said element, said locking device being movable out of engagement with the controlling means alone or out of engagement with the controlling means and the said element together, whereby either the second signal can be operated singly or the second signal and the first signal operated together, according to the position of the locking means.

8. In a device of the kind described, the combination of a signal, including a movable element, a second signal, controlling means for the second signal, said controlling means having a projection to engage the said element and hold the same against movement, means for causing the controlling means and the said element to tend to become active at a given instant, and a locking device to engage the controlling means and the said element, said locking device being movable out of engagement with the controlling means alone or out of engage-

ment with both the controlling means and the said element together, whereby when the said instant arrives the second signal will be operated alone or both signals operated together, according to the position of the locking means.

5 In testimony whereof I have signed my

name to this specification in the presence of two subscribing witnesses.

GUSTAVE J. JACCARD.
